United States Patent Office

Des. 208,976
Patented Oct. 24, 1967

208,976

CHAIR

Ernst Moeckl, Stuttgart, Germany, assignor to Lubke
K.G., Rheda, Westphalia, Germany, a corporation of Germany

Filed Nov. 19, 1965, Ser. No. 88,159

Term of patent 14 years

(Cl. D15—1)

The design is characterized by the combination on the chair disclosed comprised of a pair of rear leg supports extending vertically to the junction of a rearwardly bent backrest cushion, all as shown.

I claim:

The ornamental design for a chair, as shown and described.
